[57] CLAIM

The ornamental design for a wire reel rack for electricians, as shown and described.

DESCRIPTION

FIG. 1 is a top plan view of a wire reel rack for electricians showing my new design;

FIG. 2 is a front elevational view thereof;

FIG. 3 is a bottom plan view thereof;

FIG. 4 is a rear elevational view thereof;

FIG. 5 is a right side elevational view thereof;

FIG. 6 is a left side elevational view thereof; and

FIG. 7 is a perspective view thereof taken from above and to the left of the rack as shown in FIG. 6.

FIG. 1.

FIG. 2.

FIG. 3.

FIG. 4.

FIG. 5.

FIG. 6.

FIG. 7
